UNITED STATES PATENT OFFICE.

KENNETH SIMONDS JOHNSON, OF JERSEY CITY, NEW JERSEY, ASSIGNOR, BY MESNE ASSIGNMENTS, TO WESTERN ELECTRIC COMPANY, INCORPORATED, A CORPORATION OF NEW YORK.

TELEPHONE-SUBSTATION CIRCUIT.

1,263,421.

Specification of Letters Patent. Patented Apr. 23, 1918.

Application filed September 7, 1915. Serial No. 49,230.

To all whom it may concern:

Be it known that I, KENNETH SIMONDS JOHNSON, a citizen of the United States, residing at Jersey City, in the county of Hudson and State of New Jersey, have invented 5 certain new and useful Improvements in Telephone-Substation Circuits, of which the following is a full, clear, concise, and exact description.

10 This invention relates to a subscriber's telephone circuit of the central energy type, and has for its object to provide a circuit of this type of improved operation and efficiency.

15 In subscribers' circuits of well-known forms in which the receiver is connected with the line wires during conversation, certain inconveniences are experienced due to the flow of direct current through the receiver.

20 In accordance with this invention, these inconveniences are overcome by a combination of apparatus and circuits by means of which the flow of direct current through the receiver, when it is connected with the line circuit, is prevented. This is accomplished 25 by so connecting and combining the apparatus that the direct current potential of the receiver terminals is always the same as the potential of one of the limbs of the line circuit.

25 This invention may be applied to a known standard form of subscriber's circuit without the use of additional apparatus, wiring or contacts.

30 The regular operating features of this circuit will first be briefly described. Conductors 1 and 2 represent conductors forming a central energy line circuit which may be assumed as connected to a telephone system. It will be understood that proper ringing current for operating the ringer signal 4 may be impressed upon this line circuit at the switchboard. This ringing current path 35 may be traced from line conductor 1, winding 20 of the induction coil 16, conductors 3 and 10, winding 7 of the induction coil 16, conductor 5, condenser 21, conductors 6 and 8, ringer 4, conductor 15 to line conductor 2. 40 Upon operating the switchhook, by lifting the telephone receiver, to include the transmitter and receiver in talking relation to the line circuit, the battery path for the transmitter may be traced as follows: from line 45 conductor 1, winding 20 of the induction coil

16, conductors 3, 22, transmitter 19, conductor 23, contact spring 12, switchhook 13, conductor 14, to line conductor 2. The circuit of the telephone receiver 9 may be traced from receiver terminal 18, conductor 24, contact springs 11 and 12, conductor 23, transmitter 19, conductors 22 and 10, winding 7 of the induction coil 16, conductor 5, condenser 21, conductors 6 and 25 to terminal 17 of the telephone receiver. The order 50 in which the contact should close or open at the switchhook is preferably as shown in the drawings; contact forming first between 12 and 13, contact forming last between contacts 11 and 12. In opening, 11 and 12 disconnect 55 first, followed by 12 and 13 opening.

Although the circuit for ringer 4 is completed through the serially connected windings of the induction coil 16, the ringing efficiency is not impaired to an appreciable 60 extent.

65 In describing the means by which clicks are prevented in the telephone receiver when the switchhook is operating, it will be noted that in the normal position, the receiver 70 being on the switchhook, both terminals of the receiver are under battery potential corresponding with the potential of line conductor 2. This potential charge may be traced from line conductor 2, conductor 15, 75 ringer 4, conductors 8 and 25 to the receiver terminals. Now upon the receiver being lifted from the switchhook and the talking set thereby connected to the line circuit, both terminals of the receiver retain a potential 80 and battery polarity sign corresponding to that of line conductor 2. This path may be traced from line conductor 2, conductor 14, switchhook 13, contact springs 12 and 11, conductor 24 to receiver terminal 85 18, terminal 17 remaining common to line conductor 2 over the ringer path already traced. From the circuit connections shown 90 it will be seen that for either position of the switchhook both terminals of the receiver 95 can only be influenced by the battery potential of line conductor 2. This exclusion of battery potential influence from line conductor 1 prevents the possibility of the receiver winding receiving an impulse of 100 battery current. A further advantage of 105 this circuit is the exclusion of battery current from the receiver circuit and from the ringer circuit at all times irrespective of 110 the position of the switchhook.

What is claimed is:

1. In a subscriber's telephone circuit, in combination a central energy line circuit, an induction coil, condenser and ringer included in series in said line circuit, a transmitter circuit in parallel with said ringer, condenser and one winding of said induction coil, a receiver circuit in parallel with said ringer and means for closing said transmitter and receiver circuits.
2. In a subscriber's telephone circuit, in combination a central energy line circuit, an induction coil comprising primary and secondary windings connected in series with said line circuit, a ringer and a condenser also connected in series with said induction coil and said line circuit, a transmitter, a receiver, and switching means for including said transmitter in bridge of said line circuit in series with one winding of said induction coil and in parallel with the other winding of said induction coil, the ringer and the condenser, and for including said receiver in parallel with said ringer.
3. In a subscriber's telephone circuit, in combination a central energy line circuit, an induction coil, condenser and ringer included in series in said line circuit, a transmitter circuit in parallel with one winding of said induction coil, the condenser and the ringer, a receiver circuit in bridge of said
4. In a subscriber's telephone circuit, a pair of line conductors; a circuit connecting said line conductors and including a transmitter and one winding of an induction coil; a local branch circuit in bridge of said transmitter and including another winding of said induction coil, a condenser and a signaling device; a receiver circuit in bridge of said signaling device and switching means for closing said main circuit and said receiver circuit in sequence. 45
5. In a subscriber's telephone circuit in combination with a pair of line conductors, a main circuit including a transmitter and one winding of an induction coil; a local branch circuit including a second winding 50 of said induction coil, a condenser and a receiver in series; a signaling device connected between one terminal of said receiver and one of said line conductors, and switching means for closing said main circuit and 55 connecting the other terminal of said receiver to said line conductor.

In witness whereof, I hereunto subscribe my name this 3rd day of September, A. D. 1915.

KENNETH SIMONDS JOHNSON.
